Filed Dec. 6, 1957, Ser. No. 48,815

Term of patent 14 years

(Cl. D4—3)

FIG. 1

FIG. 2

The characteristic features of my design for the holder disclosed reside in the top shelf having the raised rib extending its entire length and the offset panel at the rear of said shelf.

I claim:

The ornamental design for a combination toothbrush and toothpaste holder, substantially as shown and described.
